UNITED STATES PATENT OFFICE

FRANK DESNOYERS PELTIER AND CLYDE EDWARD PLOEGER, OF EVANSVILLE, INDIANA, ASSIGNEES, BY MESNE ASSIGNMENTS, TO SERVEL, INC., OF NEW YORK, N. Y., A CORPORATION OF DELAWARE

REFRIGERATION

Application filed December 3, 1926. Serial No. 152,339.

Our invention relates to refrigerating apparatus and more particularly to the type of apparatus embodying a closed cycle including compressor, condenser and evaporator. 5 Our invention aims at providing a system for the artificial production of refrigeration which is simple in the number and construction of parts, the parts of which are of such nature and so devised that the apparatus as 10 a whole is more rugged and less liable to get out of order than previous devices of this class while maintaining a higher efficiency of operation. Our invention aims to produce a direct and positive flow of refrigerant with 15 advantages accruing thereto while controlling the flow in a manner such that refrigeration is produced in efficient manner independently of the parts of the system collateral to evaporation. 20 Our invention consists in apparatus for carrying out the objects above outlined and other objects which will be apparent from the following description, and further, in process carried out by said apparatus. In apparatus 25 embodying this invention flow of refrigerant through the evaporation member is preferably in one continuous path whence refrigerant passes into a larger receptacle wherein liquid refrigerant may be accumulated. 30 Variations of quantity of refrigerant in this receptacle at the outlet from the evaporator, which may be measured by variation of liquid level, are employed to regulate the supply of liquid refrigerant to the evaporation 35 member. We prefer to employ a float for controlling supply of liquid to the evaporation member because of the durability of operation of a float and because of the advantages obtained from the use of a float in connection with other phases of our invention, 40 particularly with respect to systems wherein a plurality of evaporators are coupled to a single compressor unit.

The invention is described with reference 45 to the accompanying drawings on which: Figure 1 shows diagrammatically a refrigeration system embodying principles relevant to our invention; Figure 2 is a more or less diagrammatic showing of a system embodying the invention and showing a preferred

construction of certain parts; Figure 3 is an enlarged view in section of a portion of the apparatus shown in Figure 2; and Figure 4 shows a system containing a plurality of evaporators and embodying the invention. 55

Referring more particularly to Figure 1, A designates a compressor which supplies refrigerant through pipe line B to a condenser C. The condenser is connected in series with a continuous coil evaporator D by 60 means of pipe E. Evaporator D is connected in series with a receptacle F by means of a pipe G. Receptacle F is connected in series with compressor A by means of pipe H in which last pipe there may be interposed if desired a pressure control mechanism J for controlling the operation of the compressor. Interposed in pipe E is a valve K which controls flow therethrough. Valve K may be any type of valve which can entirely cut off 70 flow through pipe E, can allow flow through pipe E, and can regulate flow through pipe E. Within receptacle F is a movable member M which is responsive to the quantity of liquid within the receptacle. This is preferably a float resting upon the surface of liquid within receptacle F. Float M is connected to valve K in any desired manner so that it will control valve K. To illustrate, float M is shown as attached to a rod O which 75 is in turn pivotally connected to the lever Q pivoted at P. The other end of lever Q is pivoted to a rod R which may be considered as the stem of valve K. It is to be understood that we do not present this arrangement as a practical solution but are using this as an illustration. Float M is connected to valve K in such manner that upon decrease of the quantity of liquid refrigerant within receptacle F and consequently upon 80 decrease of level or surface of liquid, which results in a lowering of float M, valve K is opened more or less to admit the same or a greater quantity of liquid refrigerant into the evaporator from the condenser. Conversely, upon rise of level of liquid in receptacle F float M rises and moves valve K to decrease flow through conduit E in corresponding degree. 85

It will be noted that the parts of the system 100

above described are arranged in series. The compressor, the condenser, the evaporator inlet control valve, the evaporator, the fluid receptacle, and again, the compressor, are arranged in series in the order mentioned. 5 By continuous series flow, a positive circulation of refrigerant is obtained and by means of the valve and float arrangement the amount of refrigerant contained in the evaporator is independent of the refrigerant in the rest of the system. The continuous flow evaporator permits of broader design in this unit and eliminates the necessity of obtaining circulation by gravity. 10

15 Referring more particularly to Fig. 2, a motor 2 drives compressor 3. Compressor 3 receives expanded gaseous refrigerant from conduit 24 and supplies compressed refrigerant through conduit 25 to condenser 4 which 20 may be cooled in any desired manner, either by water or by air. Condenser 4 is connected by means of conduit 7 with a valve member 23 (see Fig. 3). Valve member 23 has a central passageway 27 which constitutes a portion of 25 a continuous passageway, a part of which is within the end head 11 of a float chamber 10, said passageway being indicated at 26. Passageway 26 is connected to an evaporator coil 15. Evaporator coil 15 is formed of one 30 continuous pipe and its outlet end is connected to a passageway 30 formed within the other head 16 of the float chamber 10, opposite to head 11.

35 Valve member 23 is screwed into a recess 28 formed in head 11. The restricted end of passage 27 constitutes a valve seat indicated at 31. Valve seat 31 cooperates with a needle valve 22. Recess 28 is formed at right angles to passage 26. Needle valve 22 is formed on the end of an extended stem 32. Stem 32 40 is also arranged at right angles to passageway 26. Needle valve 22 is movable in response to variations of level of liquid within float chamber 10, which variations of level 45 are transmitted to the needle valve by means of float 18 resting upon the surface of liquid within the float chamber. This movement is transmitted through lever 19, bell-crank 20 and link 21. Float 18 is attached 50 to lever 19 which is in turn attached to bell-crank 20; bell-crank 20 is connected to link 21 and link 21 is in turn connected to stem 32 of the needle valve. Stem 32 passes with 55 relatively loose fit, but at the same time closely, through a passage or bore 34 which connects the inner liquid and vapor space of float chamber 10 with passage 26. The tightness of it may be determined in accordance with the desired balance of leakage and frictional resistance. By arranging the conduit 60 from the condenser to the evaporator in part within head 11, it is possible to control needle 22 and thus control this conduit by a simple arrangement needing no stuffing box nor bell-65 lows nor other friction producing or strained part. The amount of leakage along passageway 34 outside stem 32 is of negligible quantity. By permitting this slight leakage, a simple construction is obtained. By arranging the condenser-evaporator connection in part within the header, no leakage is possible from out of the system as a whole, while at the same time the improved control above illustrated with reference to Fig. 1 is obtained. 70

Head 11 has an opening 12 for the reception of return conduit 24 which is connected to the intake of the compressor. In conduit 24 is inserted pressure control switch 6 which may be of known type and which starts and stops the motor upon predetermined rise and fall of suction pressure. 75

The mode of operation is as follows: Gaseous refrigerant compressed in compressor 3 passes into condenser 4 where it is liquefied 80 and thence passes through conduit 7 and into opening 13, assuming that needle valve 22 is away from seat 31 so that the valve passage is open. Assuming needle valve 22 to be open, liquid refrigerant passes into coil 15 85 and a portion thereof is evaporated. Evaporation absorbs heat from the surroundings and produces refrigeration. A mixture of vaporous refrigerant and liquid refrigerant passes through opening 17 in head 16 and 90 through passageway 30 into the float chamber. Rise of liquid quantity within the float chamber causes a lifting of float 18 and this operates, through the mechanism above described, to close needle valve 22 against seat 31 to a greater or less extent, thus diminishing the flow of liquid refrigerant into the evaporator. If needle valve 22 is entirely closed, no liquid refrigerant passes from the condenser into opening 13 and into the evaporator. The compressor at the same time draws vapor through opening 12 and some of the liquid within float chamber 10 evaporates, thus lowering the liquid level therein. 95 The float 18 is consequently lowered and needle valve 22 again moves further from seat 31 to permit entry of liquid refrigerant into the evaporator. Float 18 thus operates to maintain a constant or substantially constant level within float chamber 10. 100

Referring more particularly to Figure 4, the apparatus described above is shown in arrangement suitable for use in connection with a plurality of evaporators. As shown, one condenser is employed but it is to be understood that a separate condenser may be employed for each evaporator, or two evaporators supplied from one condenser and one evaporator from another condenser, or any such combinations of condensers and evaporators may be employed without departing from the spirit of the invention. Also, any number of evaporators may be used, the number three mentioned above being a convenient one for illustration. 115

125

130

Compressed gaseous refrigerant leaves the compressor through pipe 25, is liquified in condenser 4 and passes into pipe 5. During its passage through pipe 5 the liquid refrigerant divides and passes through the various pipes denoted by reference character 7. From conduits 7 the refrigerant passes through respective float actuated expansion valves, evaporators 15 and float chambers 10 in the same manner as previously described with reference to a single evaporator system. The amount of liquid refrigerant entering each evaporator coil through the expansion valve used in connection with that coil is dependent on the liquid level in the float chamber of that float actuated expansion valve and is independent of the liquid level in any of the other float chambers or of any other conditions existing in the system.

The vaporous refrigerant after leaving the float chamber 10 passes through the respective pipes 24 to a common return pipe 14 which is connected to the suction side of the compressor. Interposed in this pipe 14 may be the pressure control switch 6 used to start and stop the motor at predetermined variations of pressure in the suction line.

It is to be understood that we are not limited to the modifications shown and described.

Having thus described our invention, what we claim is:

1. In a refrigerating apparatus, in combination, a float chamber having an inner liquid and vapor space and comprising a bounding section having a passageway through the same, both ends of said passageway terminating outside said space, a bore connecting said space with said passageway, a restriction in said passageway in line with said bore, a stem passing through said bore, a valve attached to said stem arranged to cooperate with said restriction to determine flow through said passageway and means within said space for moving said stem within said bore, said chamber comprising a single shell so that liquid therein is in direct heat transmitting relationship with the medium surrounding the shell and may be heated by the surrounding medium.

2. A refrigerating system comprising a compressor, a condenser, a valve, an evaporator and a chamber into which said evaporator discharges, said compressor, condenser, valve, evaporator and chamber being connected in series in the order mentioned and means for controlling said valve in response to variations of liquid level in said chamber, said chamber comprising a single shell so that liquid therein is in direct heat transmitting relationship with the medium surrounding the shell and may be heated by the surrounding medium.

3. In a refrigerating apparatus, in combination, a float chamber having an inner

liquid and evaporator space and comprising a bounding section having a passageway within the same, said passageway having an inlet and an outlet, both said inlet and outlet being outside said space, means to supply liquid refrigerant to said inlet, an evaporator conduit connecting said outlet with said space and valve mechanism within said bounding section for controlling flow through said passageway in accordance with variations of liquid level in said space, said chamber comprising a single shell so that liquid therein is in direct heat transmitting relationship with the medium surrounding the shell and may be heated by the surrounding medium.

4. In a refrigerating apparatus, in combination, a float chamber having an inner liquid and evaporator space and comprising a bounding section having a passageway through the same, both ends of said passageway terminating outside said space, a bore connecting said space with said passageway, a restriction in said passageway in line with said bore, a stem passing through said bore, a valve attached to said stem arranged to cooperate with said restriction to determine flow through said passageway, a float within said space and a connection between said float and said stem, said chamber comprising a single shell so that liquid therein is in direct heat transmitting relationship with the medium surrounding the shell and may be heated by the surrounding medium.

In testimony whereof we hereunto affix our signatures.

FRANK DESNOYERS PELTIER.
